CENTRIFUGAL CREAM SEPARATOR

Theodore H. Koeber, Oak Park, Ill., assignor to
International Harvester Company, a corpora-
tion of New Jersey

Application October 28, 1950, Serial No. 12,764

Term of patent 7 years

(Cl. D23—1)

To all whom it may concern:

Be it known that I, Theodore H. Koeber, a citizen of the United States, residing at Oak Park, in the county of Cook and State of Illinois, have invented a new, original, and ornamental Design for Centrifugal Cream Separator, of which the following is a specification, reference being had to the accompanying drawings, forming part thereof, in which:

Fig. 1 is a perspective view taken from one side of a centrifugal cream separator, showing my new design;

Fig. 2 is a front elevation of the centrifugal cream separator shown in Fig. 1;

Fig. 3 is a top plan view of the centrifugal cream separator shown in Figs. 1 and 2; and

Fig. 4 is a plan sectional view taken along the line 4—4 of Fig. 1.

I claim:
The ornamental design for a centrifugal cream separator, as shown.

THEODORE H. KOEBER.
